UNITED STATES PATENT OFFICE.

ENOCH C. BOWLING, OF YPSILANTI, MICHIGAN, ASSIGNOR OF ONE-HALF
TO HENRY P. GLOVER, OF SAME PLACE.

GARMENT-STAY.

SPECIFICATION forming part of Letters Patent No. 378,080, dated February 21, 1888.

Application filed August 18, 1887. Serial No. 247,265. (No model.)

To all whom it may concern:

Be it known that I, ENOCH C. BOWLING, a citizen of the United States, residing at Ypsilanti, in the county of Washtenaw and State 5 of Michigan, have invented certain new and useful Improvements in Garment-Stays; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to garment-stays, particularly to the construction of parts and means employed for securing the metallic end caps to the ends of the flexible blade, said caps being provided with an impervious coating, which cements said caps to the blade and to the outer textile covering fabrics.

20 The object of my present improvement is to more securely cover the ends of the stiffening-blade by providing said ends with metal 25 caps or covers, which are U-shaped and concavo-convex in cross-section, being adapted to receive in the concave the square ends of the stiffening-blades, thus forming rounded ends to the blade, avoiding the sharp corners 30 thereof, and preventing the ends of the stiffening-blades from working through the coverings of the stay and puncturing the garment, to the open seam of which they are attached by stitching through the fabric-stitching-edges 35 formed along the edges of the stay, which will be hereinafter more fully set forth.

To more readily comprehend the merits of my invention, reference should be had to the accompanying drawings, in which—

40 Figure 1 is an isometrical view of a number of stays in sheet form, which are to be separated, as indicated by dotted lines. Fig. 2 is a view of same having the covering fabrics and sheets of gutta-percha tissue turned back at one 45 end to show position of parts prior to sealing. Fig. 3 is an isometrical view of a single stay as it appears when completed. Fig. 4 is an enlarged vertical longitudinal section taken on dotted line 11 of Fig. 3. Fig. 5 is a perspective of the metal cap or cover.

In the drawings, Fig. 1, B B represent the outer covering fabrics of the stiffening-blade, and Z Z the interposed sheets of gutta-percha tissue. *a* shows the pinked or scalloped edges of the coverings, and *f* the stitching-edges 55 formed along the edges of the stay by the projection of the gutta-percha tissue and outer covering fabrics.

In Fig. 2, D represents the steel or stiffening-blades, and E the metal caps or covers on 60 the ends of the stiffening-blades. Said caps are formed from a single piece of metal, being spun or pressed in the shape of a U, and concavo-convex in cross-section, as shown in Fig. 5.

The concave K of each cap or cover is 65 adapted to receive the square ends of the stiffening-blade, being secured thereon by pressing down onto the body of the blades D, to prevent said caps from dropping off while the coverings are being applied to the stiffening- 70 blades, which, when the parts are sealed, will be held more firmly to the stiffening-blades by the union of said coverings.

In constructing my improved stay the operations are as follows: The covering fabric C 75 and sheet of gutta-percha tissue Z are first placed upon a suitable support. The caps E are placed, as specified, on the ends of the stiffening-blades, and after first being sufficiently warmed to adhere to the gutta-percha tissue- 80 sheets the blades are placed thereon at a slight distance apart. The sheet of gutta-percha tissue Z and covering fabric B are then placed over the series of blades, and by applying a heated plate or iron to the upper face of the 85 sheet of goods the interposed sheets of gutta-percha tissue, by the heat, become soft or melted and adhere to the stiffening-blades and covering fabrics, thus uniting the parts together and forming an impervious coating 90 around the stiffening-blades and metal caps, which will prevent moisture or perspiration from the body of the wearer from coming in contact with the steel blades, which otherwise would cause them to rust.

95 I am aware that metallic end caps secured to the ends of stiffening-blades for corsets and stays have long been in use, and therefore do not claim, broadly, such matter; but I am not aware that stiffening-blades hav- 100

ing such metallic end caps have heretofore been secured within a covering of fabric having interposed layers of gutta-percha tissue, with a marginal or fabric stitching-edge surrounding said protected blade and metallic end caps, whereby said blades and metallic end caps are provided with an impervious coating having an outer textile covering, the gutta-percha tissue cementing the end caps firmly to the ends of the blade and within the textile fabric coverings, whereby said metallic parts are prevented from rusting or corroding, the metallic end caps being cemented within the fabrics, thereby preventing said caps from pulling off the blade, as is common when attached in the ordinary way to the exterior of the stay, by simply pressing said caps onto the ends of the stay.

Having thus fully set forth my invention, what I claim as new, and desire to secure by 20 Letters Patent, is—

The herein-described stay, comprising the stiffening-blade having metallic end caps, and fabric coverings projecting beyond the edges and capped ends of the stiffening-blade, with 25 interposed sheets of gutta-percha tissue, said parts adhering together and forming the textile fabric stitching-edges *ff*, as and for the purposes specified.

In testimony whereof I affix my signature in 30 presence of two witnesses.

ENOCH C. BOWLING.
